APPARATUS FOR REFORMING AND FORMING RAIL END BALLS

Original Filed Nov. 7, 1939

UNITED STATES PATENT OFFICE

2,375,470

APPARATUS FOR REFORMING AND
FORMING RAIL END BALLS

Albert E. Hill, Detroit, Mich.

Original application November 7, 1939, Serial No.
303,269. Divided and this application February
4, 1943, Serial No. 474,710

14 Claims. (Cl. 78—76)

This invention is directed to an apparatus for restoring worn or deformed rail ends to the end that both sides of the rails may accurately serve as the gauge side and so that the fishing heights are closed and equalized.

This application is filed as a division of my application, filed November 7, 1939, Serial number 303,269, now issued as Patent No. 2,313,034, dated March 2, 1943.

The improved apparatus is designed for expeditious and convenient assembly with and operation with respect to heated rail ends, to insure effective function of the apparatus while the rails remain sufficiently heated.

It has been heretofore proposed to remedy the worn rail ends by pressing a recess through the ball of the rail at each rail end. This method, however, resulted in closing the fishing height of the rails directly against new splice bars and in an attempt to keep the gauge sides of the rails straight and recess the opposite side. This method proved objectionable for in heating the rail ends for recessing and forcing the lower faces of the rails into contact with the splice bars, the rail ends shrunk and the splice bars, and rail-end balls, were not in bearing contact.

It is important in an apparatus of this type that the rail ends be not deformed to an extent to unfit the rails for reversal, as frequently necessary to present new gauge sides, and furthermore, the metal of the rail ends at their extreme margins should remain intact to avoid disturbing the fiber of the grain of the metal to avoid any possibility of the rail ball splitting on the line of the swaged indication.

A primary object of the invention is therefore, to restore worn or deformed rail balls at adjacent end portions to insure that both sides of the rails may accurately serve as gauge sides, and that the fishing heights of the rails are closed and equalized.

A further object of the invention is in providing a result wherein the load stresses are removed from the extreme rail ends to thereby increase the strength of the splice bars that such may be fully utilized, while the danger of rail-end splitting is avoided.

The invention is illustrated in the accompanying drawing, in which:

Fig. 1 is a perspective view, partly in section, showing the improved apparatus in cooperative engagement with a rail.

Fig. 2 is a view in end elevation, partly in section, on the line 10—10 of Fig. 1.

Fig. 3 is a fragmental transverse sectional view, showing the correlation of the anvils and swaging tool with a deformed rail.

Fig. 4 is a similar view showing the completion of the swaging operation.

Fig. 5 is a side elevation of one of the rail-end spacings, the end of the rail being in dotted outline.

Fig. 6 is a side elevation of adjacent ends of a pair of deformed rails, the spacing plate and anvils being in longitudinal section.

Fig. 7 is a similar view showing the relation between the anvils and balls of the rail ends following the swaging operation.

Fig. 8 is a horizontal sectional view, taken substantially on the line 16—16 of Fig. 2.

The improved apparatus, forming the subject of this invention, comprises a pair of lower anvils 30, beyond each of which is arranged a bracket 31, connected in laterally-spaced relation to the adjacent anvil by spaced pins 32, the relatively inner ends of which are threaded or otherwise connected to the anvil, and which have outer headed ends extending through apertures in the bracket.

A wedging bolt 33 is carried by and adjacent each end of each bracket 31, the wedging bolts being pinned to the bracket at 34. The wedging bolts are arranged beyond the pins 32 and at their inner ends pass through openings 35 in the anvils 30. The openings 35 in the anvil 30 register, when the apparatus is in operative position, with conventional bolt holes in the web of the rail R, and springs 36, coiled loosely on the wedging bolts bear between the anvils 30 and the bracket 31. This construction is illustrated more particularly in Figs. 2 and 8.

An upper anvil 37 is arranged for cooperation with the ball of the rail R, and is shaped to overlie and more or less conform to the shape of the rail ball, having relatively heavy side walls depending below the sides of the rail ball, as shown in Fig. 2. This upper anvil is designed to cooperate with the lower anvils to confine the flow of metal in the operation of the apparatus to proper areas.

The upper anvil 37 is connected with the lower anvil supporting brackets 31 through the medium of a rigid, preferably integral rib 38, extending longitudinally of the upper surface of the upper anvil, with such rib provided with longitudinally spaced laterally arranged lugs 39. The lugs 39 extend above and beyond the rib 38, and overlie and are rigid, preferably integral with the upper

surface and sides of the upper anvil 37. The lugs 39 are formed to provide longitudinally aligned top pivot ears 40 and side pivot ears 41, respectively receiving pivot pins 42 and 43. The brackets 31 are each provided with pivot ears 44, in vertical register with the side pivot ears 41 of the lugs 39.

A rocker arm 47 is rigid with the pivot pin 42, being centrally fixed to such pin and arranged between the ears 40. A manually-operable lever handle 48 is secured to one end of the pivot pin 42, to provide for operating the rocker arm 47. Vertically disposed levers 46 are pivotally mounted at their lower ends on pins 45, passing through the ears 44 of the brackets 31, such levers 46 being further pivotally mounted on pins 43, which as stated, are carried by the ears 41 of the lugs 39. The upper ends of the levers 46 are connected by links 49 with the adjacent ends of the rocker arm 47.

The upper anvil 37 is formed at the forward edge of the surface in contact with the rail ball with a cut-away or beveled face 50, serving in operation of the apparatus, to form a beveled complementary formation in the extreme edge of the upper portion of the ball of the rail R, as clearly shown in Fig. 1.

Swaging tools are mounted for movement at right angles to the sides of the ball of the rail, said tools serving to form in each side of the rail ball a limited and specifically disposed recess, indicated at 10 in Fig. 1. The swaging tools are preferably formed as rectangular plates of appropriate thickness, shown at 52, having an enlarged driving head 53, and are each formed on the edge next the rail ball with a forming projection 58, appropriately formed and positioned to form the desired recesses 10 in the rail ball. The swaging tools are mounted for support in an appropriately-formed opening 54 in the side plates of the upper anvil 37, a pin 56, pinned to the upper anvil at 57, passing through such anvil and wedging tool.

In the use of the apparatus, one complete assembly is arranged on the ends of adjacent rails R, a spacing plate 60 of appropriate thickness for rail spacing between such rail ends being positioned therebetween, as shown in Fig. 6. The rails are initially heated to the required degree, and following the application of the apparatus, disposed as described, the handle or handles 48 are moved from a normal horizontal position to a vertical position. The lower ends of the levers 46 are thus moved toward each other by the operation of the rocker arm 47 through the links 49, causing the brackets 31 to be forced toward the adjacent rail web against the tension of the springs 36. The wedging bolts move into lapping relation with the conventional holes in the rail web, and as these bolts move through slightly-enlarged holes in the lower anvil, such wedging bolt movement forces the lower anvils into engagement with the base flanges of the rail. The lower anvils are of fishing height of the rails and, incident to the pressure of the springs 36, forced into contact with the rail web. This provides any fishing height difference in the worn or deformed rail to be above the upper edges of the lower anvils, and which is to be compensated for in the swaging operation.

The lower anvils are to be formed so that the fishing height is provided to allow for the closing of such fishing height to compensate for both wear under the rail head and on top of the splice bars, and also to allow for shrinkage when the

heated rail cools. The desired purpose here is that the reformed rail will be correctly finished for the application of the old splice bars, even in worn condition.

5 The spacing plates 60 which are arranged between the ends of adjacent rails and also between the respective apparatus of the present invention, serve to prevent flow of metal during operation and also such plates form a stop to 10 properly position and locate the improved apparatus.

15 After positioning the apparatus, as described, and if desired during operative movement of the lever 48, a light blow is given the upper surface of the upper anvil, preferably on an impact extension 51 carried by such upper anvil. This 20 compels a movement of the upper anvil, serving to reform the upper surface of the rail ball, and particularly the beveled end of such ball, indicated at 17, Fig. 1. The swaging tools 52 are 25 then forced forward toward the rail ball, preferably by blows delivered on the tool heads 53, forcing the projections 48 into the metal of the rail ball, which by reason of the heated condition is forced to flow or be dispersed, the displacement being limited by the sides of the upper anvil, the lower anvils 30, and the plate 60.

30 The displacement of the metal is limited by the upper anvil and ultimately provides projections 61, Fig. 1, to define the proper fishing height of the rail. The flow of metal in forming the recess in the rail end is limited in the downward direction, and provides a small section of metal which is thus compacted or moved 35 into a position where the rolling impact on the rail end is the greatest.

35 By locating the recess 10 with relation to the depending projections 61, so that the ends of such recesses and projections at the ends of the 40 same remote from the rail end are in substantial alignment, and extending the opposite end of the recesses beyond the proximate end of the projection, while still maintaining the end of the recess inwardly of the extreme rail end, an important advantage is gained. In use the greatest load stress on the rail is not on the end fiber of the rail web. By having a small zone of metal on the end of the rail web between the beginning and end of the stress section, the strength of the 45 splice bar is increased and the danger of splitting the web and breaking off a piece thereof at the end of the ball by progressive fractures starting at the end of the web is practically completely avoided.

50 The construction described is described in substantial detail in accordance with preferred arrangement. Obviously, variations of structure and the use of mechanically equivalent parts, leading to the defined result may be used without departing from the spirit of the present invention, and any and all such variations as fall within the 55 scope of the appended claims are contemplated as within the invention defined.

55 For example, in the above connection, while it is understood that the recesses in the rail ball formed by the swaging tools shall not extend to the proximate end of the ball, it is apparent that the depth of the recess, so long as it does not extend through the rail ball, as well as its outline 60 form can be arranged with particular regard to the requirements of the particular job, and that correspondingly the form of the swaging-tool projection can be correspondingly shaped, as required. Again the obvious necessity of meeting 65 different fishing heights relative to worn or re-

placed splice bars, will necessitate adjustment in the position and relation of the lower anvils. These details are fairly included variations, seeking to accommodate the apparatus to substantially any worn construction that may be sought to be corrected, and that any and all such variations are merely mechanical changes within the present disclosure to secure the desired result.

What is claimed as new, is:

1. An apparatus of the class described, including an upper anvil, lower anvils, brackets arranged outwardly of the lower anvils, means carried by the brackets for supporting the lower anvils, and manually-operable means carried by the upper anvil and connected to the brackets for forcing the latter and thereby the lower anvils in an operative direction. 10

2. A construction as defined in claim 1, wherein means are provided for guiding the lower anvils in operative movement to compel a relative predetermined lowering of such anvils. 15

3. A construction as defined in claim 1, wherein the upper anvil is designed to cooperate with the ball of a rail, and wherein swaging tools are mounted in the upper anvil in predetermined relation to the lower anvils. 20

4. An apparatus of the type described, including an upper anvil, lower anvils, brackets slidably supporting the lower anvils, and means for supporting the brackets from the upper anvil, said means being operable to compel movement of the brackets and thereby of the lower anvils in a predetermined direction. 25

5. An apparatus of the type described including an upper anvil formed to fit over the ball of a rail and overlie the sides thereof, brackets supported by said upper anvil, lower anvils carried by the brackets and movable relative thereto, and swaging tools carried by the sides of the upper anvil and overlying and extending beyond the brackets to provide impact heads. 30

6. A construction as defined in claim 5, wherein the operative ends of the swaging tools are provided with rail-ball forming recess-defining projections, positioned in definite relation to the lower anvils. 35

7. An apparatus of the type described, including an upper anvil, lower anvils, brackets supporting the lower anvils, swaging tools removably carried by the upper anvil, means for operating the brackets and thereby the lower anvils relative to the upper anvil, and rail-ball end forming means on the upper anvil. 40

8. A construction as defined in claim 13, where-

in the swaging tools are mounted for a predetermined limited movement in and relative to the upper anvil.

9. An apparatus of the class described, including a pair of lower anvils to be supported on opposite sides of a rail web, an upper anvil for cooperation with the rail ball, swaging means slidably supported by the upper anvil, and wedging elements supported by the upper anvil and movable relative thereto, said wedging elements operatively cooperating with the lower anvils for moving the lower anvils toward and from the rail web. 45

10. A construction as defined in claim 9, wherein springs are provided for forcing the lower anvils into yielding contact with the rail web, and wherein bolts are provided to cooperate with the lower anvils and with the conventional bolt holes in the rail web to force the lower anvils toward the base flanges of the rail. 50

11. A construction as defined in claim 9, wherein the swaging means carry impact heads at one end and recess-forming projections at the other, and wherein the upper anvil is formed to provide a bevel on the ball end in operation.

12. An apparatus of the type described, including a pair of lower anvils to be disposed at opposite sides of a rail web, a bracket arranged laterally of each anvil and slidably connected therewith, an upper anvil arranged in cooperative relation with the top and sides of the rail ball, a rib integral with the upper anvil, and manually-operable connections between the rib and brackets and thereby the lower anvils relative to the rail web. 55

13. A construction as defined in claim 12, wherein the manually-operable connections comprise a rocker arm pivotally supported by the rib, a lever for operating said rocker arm, levers pivotally connected at their lower ends to the brackets, said levers being pivotally supported intermediate their ends by the rib, and connections between the upper ends of the levers and the rocker arm. 60

14. A construction as defined in claim 12, wherein the manually-operable connections comprise a rocker arm pivotally supported by the rib, a lever for operating said rocker arm, levers pivotally connected at their lower ends to the brackets, said levers being pivotally supported intermediate their ends by the rib, and links pivotally connected to the levers and to the rocker arm. 65
